UNITED STATES PATENT OFFICE.

ELEANOR D. SON, OF UTICA, NEW YORK.

DESIGN FOR A TAILPIECE FOR STRINGED INSTRUMENTS.

SPECIFICATION forming part of Design No. 28,507, dated April 26, 1898.

Application filed February 21, 1898. Serial No. 671,202. Term of patent 7 years.

To all whom it may concern:

Be it known that I, ELEANOR D. SON, a citizen of the United States, residing at Utica, in the county of Oneida and State of New York, have invented and produced a new and original Design for Tailpieces for Stringed Instruments; and I do hereby declare the following to be a full, clear, and exact description of the same, reference being had to the accompanying drawing, forming a part thereof.

In the accompanying drawing the figure is a perspective view of a tailpiece for stringed musical instruments embodying my design.

The essential feature of my design consists of a body portion having a downwardly-turned rear end and its forward end turned upwardly and backwardly and slit at intervals to form finger-like configurations.

A in the drawing represents the body por-

tion, which is elongated and has its edges formed on graceful curves, its rear end being turned down, as at a , and its forward end being turned upwardly and backwardly, as at a' , upon which appear longitudinally-arranged slits a^2 , forming finger-like configurations a^3 , with a space a^4 beneath the fingers. 25

Having now described my invention, what I claim as new, and desire to secure by Letters Patent, is—

The design for a tailpiece for stringed instruments, substantially as herein shown and described.

In testimony whereof I affix my signature 35 in presence of two witnesses.

ELEANOR D. SON.
